UNITED STATES PATENT OFFICE

RAYMOND T. CLOUD, OF CHICAGO, ILLINOIS, ASSIGNOR TO ORCHESTRAPHONE COMPANY, OF CHICAGO, ILLINOIS, A CORPORATION OF DELAWARE

PICK-UP AND CARRIER THEREFOR

Application filed July 16, 1928, Serial No. 293,098. Renewed August 14, 1931.

This invention pertains to apparatus for reproducing sound waves such for example as music, and more particularly to a pick-up supported by a tone arm and carrier therefor adapted for use in connection with the electrical reproduction of music from phonograph records and the like.

An object of my invention is the provision of a pick-up arm carrier of simple and inexpensive construction and adapted to be associated with the arm without in any way interfering with the operation of the pick-up during the time that it is in cooperation with the record being reproduced.

Another object of the invention resides in the provision of a pick-up arm carrier including electromagnetic means for holding the pick-up on the tone arm out of cooperation with the record.

In accordance with the general features of my invention I provide a carrier for a tone arm mounted on a common axis with the tone arm and including electromagnetic means for holding the reproducer on the end of the tone arm out of cooperation with the record.

Another feature of my invention resides in the provision of a common mounting for the tone arm and carrier which permits of the carrier being moved away from the tone arm after the tone arm has been lowered into cooperation with the record.

Still another feature of this invention has to do with the provision of a carrier having adjustable means for engaging the reproducer on a tone arm designed to hold the reproducer on the tone arm at various distances from the record.

A further feature of the invention relates to the provision of a common mounting for a tone arm and carrier which mounting includes stops for limiting the movement of the carrier as well as of the tone arm.

Other objects and advantages of my invention will more fully appear from the following detailed description taken in connection with the accompanying drawings which illustrate a single embodiment thereof and in which:

Figure 1 is a plan view of a tone arm and

carrier therefor embodying the features of my invention;

Figure 2 is a side elevation of the structure shown in Figure 1 and illustrating the tone arm as being held out of cooperation with a record on a phonograph turntable; 55

Figure 3 is a fragmentary sectional view taken on substantially the line III-III of Figure 1 looking in the direction indicated by the arrows and showing by dotted lines the position of the mechanism when the reproducer on the tone arm is in cooperation with the record; 60

Figure 4 is a horizontal section through the tone arm; 65

Figure 5 is an enlarged fragmentary detail view, partly in section, of the electromagnetically operated mechanism in the tone arm carrier;

Figure 6 is a fragmentary sectional view taken on substantially the line VI-VI of Figure 5 looking in the direction indicated by the arrows; 70

Figure 7 is a fragmentary plan view of certain of the details shown in Figure 5; 75

Figure 8 is a fragmentary vertical sectional view taken on the line VIII-VIII of Figure 5;

Figure 9 is a fragmentary sectional view illustrating the adjustable stud for engaging the extension on the reproducer of the tone arm, and 80

Figure 10 is a view taken on the line X-X of Figure 2 looking upwardly and illustrating the construction of the lower end of the mounting for the tone arm and carrier. 85

In the drawings:

Like reference characters designate similar parts throughout the several views. The reference character 15 designates generally a tone arm having one end 16 bifurcated, as illustrated in Figure 4, so as to accommodate one end of a tone arm extension 17. This end of the extension 17 has secured to it a pin 18, the ends of which are journaled in anti-frictional elements 19 carried by the legs of the bifurcated end 16 of the tone arm proper. Each of the anti-frictional elements 19 is held in place by washers 20, 21, and a bolt 22 90 95 100

threaded into the corresponding end of the pin 18.

The other end of the tone arm extension 17 carries a reproducer designated generally by the reference character 25, which in the present instance comprises an electrical pickup for reproducing the sound waves on a record 26 which may be of the phonograph type disposed on a phonograph turntable 27. The turntable 27 may be operated continuously by any suitable mechanism such, for example, as a conventional electric motor (not shown).

The reproducer 25 comprises an enlarged housing 28 in which is disposed the electrical pickup mechanism designated generally by the reference character 29 in Figure 4. This pickup mechanism may be of the same character as that disclosed in my copending patent application Serial No. 234,447 filed November 19th, 1927. This pickup mechanism 29 is operatively connected to a needle holder 30 adapted to receive a needle 31 for cooperation with a record 26. The waves recorded in the electrical pickup 29 are transmitted through electrical conductors 32 extending through the tubular extension 17 and the tubular tone arm 15 to a suitable amplifier (not shown). Also the housing 28 has connected to it an extension 34 including a spherical portion 35 arranged for cooperation with the holding means in the carrier which will be more fully described hereinafter.

From the illustrations of the tone arm in Figures 1 and 4 it will be evident that the tone arm extension 17 including the reproducer 25 can be pivoted upwardly over the top of the tone arm 15 proper in much the same manner as the reproducer on a phonograph is pivoted to a position above the tone arm. Also it will be noted that the tone arm 15 includes a mounting portion 36 including a central bore 37 (Figures 3 and 4) in which is tightly fitted one end of a tubular element 38. This element 38 is journaled in spaced anti-frictional elements 39 and 40 which will be more fully described hereinafter in connection with the mounting for the tone arm and carrier. I shall now proceed with the description of my novel carrier for the tone arm.

The tone arm carrier is designated generally by the reference character 45 and includes an extension 46 rotatably mounted upon a fixed mounting tube 48 which will be more fully described hereinafter. The carrier 45 includes a hollow housing 49 out of which extends the free end of a pivotally mounted member 50. The free end of this member 50, as shown in Figure 9, has a threaded opening 51 into which is threaded one end of a stud 52 having its upper end formed into an enlarged portion 53 defining an arcuate seat 54 designed to accommodate and receive the spherical portion 35 on the extension 34 of the reproducer 25. It will be evident that

the stud 52 is adjustable to various positions whereby it can hold the pickup arm at various distances from the record 26 (Figure 2). After the stud 52 has been adjusted to the desired position it may be held in that position by the setscrew 55 threaded into the free end of the pivotally mounted lever member 50. The other end of the member 50 is pivotally mounted upon a pin 56 secured to the side walls of the carrier housing 49.

The underside of the carrier rod 50 has formed integral with it a slanting or tapered surface comprising a cam 57 (Figure 5) co-operable with rollers 58 rotatably carried by the squared portion 59 of a plunger rod 60. Each of the rollers 58 (Figure 7) includes a reduced portion 61 arranged for engagement with the cam portion 57. It will be noted that the cam portion 57 is of a slightly less thickness than that of the member 50 proper, so that this cam portion extends between the inner edges of the rollers 58.

One end of the rod 60 extends through an apertured lateral extension 64 formed integral with the base plate 65 of the carrier. The portion of the rod 60 between the rollers and the extension 64, as shown in Figure 5, is enlarged and formed into a squared portion designated generally by the reference character 65 adapted to abut the extension 64 to limit the outward travel of the plunger 60. The other end of the rod 60 is connected by a pin 67 to one end of a piston rod 68, the other end of which rod 68 has formed integral with it a piston 70. It will be noted that one end of the rod 68 extends through the bifurcated end 71 of the plunger 60 and has secured to it the pin 67 which extends into slots 72 formed in the legs of the bifurcated end 70 of the plunger rod 60 (Figure 7).

The piston 70 is reciprocable in the cylinder bore 73 formed in the metal block 74. One end of the bore 73 is at all times closed by means of a closure plug 75 rigidly connected to the block 74 (Figure 3). The piston 70 is formed tubular so as to accommodate one end of a compression spring 76, the other end of the spring abutting the closure plug 75. This spring is at all times adapted to urge the piston in a direction away from the closure plug 75.

The base plate 65 of the carrier housing 49 is secured to the cylinder block 74 which is in turn secured to a frame plate 77. This frame plate is right angular in construction, one leg of which extends in front of the mechanism shown in Figure 3, but is not illustrated in the drawings for sake of clearness, and the other leg of which being shown in Figure 3 as serving for a support for the electromagnetic coil 78. It is, of course, to be noted that the frame member 77 as well as the coil 78 are disposed within the carrier housing 49.

The coil 78 is positioned in a horizontal plane and has one of its ends rigidly secured to the vertical leg of a metallic angular member 79. The vertical leg of the angular member 79 is rigidly fastened to the leg of the plate 77 shown in Figure 3. Also the top surface of the horizontal leg of this angular member 79 abuts a lug 80 formed integral with and extending inwardly from the carrier housing 49. Bolts 81 serve to fasten this horizontal leg of the angular iron member 79 to the lug 80 so as to rigidly hold the coil in place within the carrier housing 49.

Associated with the free end of the electromagnetic coil 78 is a right angular armature 82, one leg of which is disposed adjacent the core of the coil and the other or horizontal leg of which extends over the horizontal leg of the angular member 79. This angular member 82 is pivotally connected to the edge of the horizontal leg of member 79 by a stud 83 extending through a slot formed in the member 82 at its vertex.

The horizontal leg of the angular armature 82 has secured to it a U-shaped element 85, the legs of which straddle the electromagnetic coil 78 and have their lower ends associated with the plunger rod 60. In Figure 3 it will be noted that the lower ends of the legs of this element 85 are connected by a pin 86 upon which is mounted a rotatable roller 87. This roller is designed to engage aligned notches 88 (Figure 5) formed in the bifurcated end 71 of the plunger rod 60. The purpose of the roller 87 is to cooperate with the U-shaped element 85 and the armature 82 in holding the plunger rod 60 and the piston 70 in the positions shown in Figure 3 so that the member or arm 50 will be maintained in its uppermost position. In other words, the energization of the coil 78 attracts the vertical leg of the armature 82 causing the U-shaped element 85 to be moved upwardly, whereby the roller will engage in the aligned grooves 88 of plunger rod 60 when the plunger rod 60 is moved into its retracted position within the carrier housing 49.

In the assembly of the carrier 45, the electromagnetic coil and the associated plunger rod mechanism is mounted as a unit within the carrier housing 49 and suitably anchored therein. The housing 49 has threaded in it an adjusting screw 90, the end of the shank 55 of which is adapted to engage the top surface of the member or arm 50 and to thus serve as a stop to limit the upward travel of this member 50.

I shall now proceed to describe in detail the novel mounting for the carrier and the tone arm which I have previously referred to in a general way. The fixed tubular member 48 upon which the carrier 45 is pivotally mounted extends through an opening formed 65 in the supporting board 91 (Figure 3).

Threaded on to this fixed tube 48 is a tubular mounting element 92 having a circular flange 93 formed on its top end for engaging the top surface of the board 91. It will be evident that when this member 92 is in the position shown in Figure 3 it will serve as a means for holding the carrier and tone arm in place on the supporting board 91. Threaded into the member 92 is a setscrew 94, the inner end of which is adapted to extend into an annular groove 95 formed in the periphery of the tube 48 for the purpose of anchoring the tube 48 against rotation.

As shown in Figures 1 and 10, the annular flange 93 has a portion cut away as indicated at 96 so as not to interfere with a tube of insulation 97 secured to the housing 49 of the carrier. The conductors 98 for the electromagnetic coil 78 are threaded through this tube 97 as will be evident from Figure 2.

Also in Figure 1 it will be evident that the extension 46 of the carrier includes an annular flange 99 disposed adjacent the top surface of the flange 93 of tube 92. A portion of this flange is cut away as indicated at 100 so as to accommodate the stop screw or pin 101 secured to flange 93. This pin 101 is designed to cooperate with the shoulders formed by the cut out portion 100 so as to limit the movement of the carrier 45 about the axis of the fixed tube 48.

In Figure 3 it will be noted that the mounting portion 36 of the tone arm abuts the top of the extension 46 of the carrier and is rotatably mounted upon the top edge of the fixed tube 48. The extension of the mounting portion 36 comprising the tubular element 38, as previously pointed out, is journaled in the spaced ball bearings or anti-frictional elements 39 and 40 mounted within the interior of the fixed tube 48. The lower end of the tubular element 38 has mounted on it a collar 104 secured thereto by a setscrew 105 (Figure 10).

Attention is directed to the fact that the lower end of the fixed tube 48 is formed into a hexagonal shape so as to facilitate the unthreading of the tube from the tubular element 92 when the parts are being disassembled. The collar 104, as shown in Figure 10, is disposed within this hexagonal portion which is designated by the reference character 106. A portion of the hexagonal end of the fixed tube 48 is cut away so as to provide a slot 107 for accommodating the head of stop screw 108 secured to collar 104. The shoulders defining the slot 107 are adapted to cooperate with the stop screw 108 in limiting the travel of the tubular element 38. Obviously since the upper end of the tubular element is tightly fitted in the mounting portion 36 of the tone arm, it necessarily follows that by limiting the movement of this tubular element the movement of the tone arm about the axis of the fixed tube 48 will also be lim-

ited. Incidentally, it will be noted that the wires 32 for the electrical pickup 29 are threaded through the bore of the tubular element 38 as shown in Figure 3.

5 The operation of the above described mechanism is briefly as follows: To effect raising of the needle 31 out of cooperation with the record 26, the plunger rod 60 is moved inwardly into the carrier housing 49, thus causing piston 70 to compress the spring 76. During movement of the piston into the cylindrical bore 73 of the piston block 74, air is forced from the bore and escapes out of the block around the periphery of the piston 70. 10 Moreover, upon the grooves 72 in the end 71 of the plunger rod 60 reaching a position opposite the roller 87, the energized coil 78 immediately acts upon the pivotally mounted armature 82 to draw the U-shaped element 15 85 upwardly so as to cause the roller 87 to be wedged in the grooves 72 thus resulting in the plunger rod 60 being locked in the position shown in Figure 3.

It will, of course, be evident from Figure 25 5 that during the above discussed movement of the plunger rod 60 the rollers 58 engage the slanting or cam portion 57 thereby gradually moving the pivoted member 50 to its uppermost position shown in Figure 3. 30 Thereafter, if the spherical portion 35 of the pickup housing 28 be placed on the curved surface 54 of the head 53 of stud 52, the needle 31 will be clear of and above the plane of the record 26 on turntable 27.

35 When it is desired to lower the pickup 25 into cooperation with the record 26, the same may be effected by de-energizing the electromagnetic coil 78 which results in the U-shaped element 85 gravitating to its lowermost position whereby the roller 87 is moved out of cooperation with the grooves 72 in the end 71 of the plunger rod 60. This allows the compressed spring 76 in the piston 70 to become active to urge the piston outwardly 40 and away from the closure plug 75. The movement of the piston in a direction away from the plug, however, is retarded due to the fact that the air pressure on the outer side of the piston is greater than that prevailing in the interior of the piston and in the cylindrical bore 73. That is to say, as the piston is forced in a direction away from the plug by the spring, the air gradually leaks into the interior of the cylinder around 45 the periphery of the piston so as to equalize the air pressure on both ends of the piston. This equalization of pressures is gradual so that the piston 70 is in effect cushioned by air as it is moved under the effect of the 50 spring 44.

This gradual movement of the piston by the spring results in the lowering of the pivoted member 50 whereby the pickup needle 31 is slowly lowered into cooperation with the groove of the record 26. In other words,

the lowering of the pickup itself is in reality resisted by an air cushion so as to prevent the needle from falling with force into contact with the record.

Furthermore, it will also be evident that 70 when the pickup 25 is supported by the carrier 45, both the carrier and the pickup may be swung about the axis of tube 48 to a position in which it is desired to lower the pickup so as to cause its needle 31 to engage the record. Thereafter, the de-energization of the electromagnetic coil results in the gradual lowering of the needle into engagement with the record as previously described. When the pickup is in cooperation with the record, the carrier 45 (Figure 1) can be swung in a 75 clockwise direction clear of the tone arm and pickup.

It is also to be noted that the pivotal movement of the tone arm 15 and its pickup 25 is 80 limited by the head of screw 108 engaging the abutments or shoulders defined by the cut out portion 107 in the lower or hexagonal end 106 of tube 48 (Figure 10). The 85 pivotal movement of the carrier 45 is limited by the head of screw 101 engaging the shoulders or abutments of the flange 99 connected to the extension 46 of the carrier.

Now, of course, it is to be understood that 90 although I have illustrated and described in detail the preferred form of my invention, the invention is not to be thus limited, but only in so far as defined by the scope and 95 spirit of the appended claims.

I claim as my invention:

1. In combination, an arm, reproducing means connected to the arm for cooperation with a record, means for holding the reproducing means out of cooperation with the record, means for releasing said holding means so as to allow said reproducing means to move into cooperation with the record, a mounting for said arm, and a mounting for said holding means, said mountings being disposed in axial alignment and arranged so that said arm and holding means are swingable independently of each other. 100

2. In combination, an arm, reproducing means connected to the arm for cooperation with a record, means for holding the reproducing means out of cooperation with the record, means for releasing said holding means so as to allow said reproducing means to move into cooperation with the record, a mounting for said arm, and a mounting for 105 said holding means, said mountings being disposed in axial alignment, said arm and holding means each being independently swingable about a common axis. 115

3. In combination, an electrical pickup for reproducing the recorded waves on a given record, and a carrier independent of but associated with the pickup including means for holding the pickup out of cooperation with the record and electromagnetic means for re- 120 125

leasing the holding means to allow the pickup to gravitate into engagement with the record.

4. In combination, an electrical pickup for reproducing the recorded waves on a given record, a carrier associated with the pickup including means for holding the pickup out of cooperation with the record and electromagnetic means for releasing the holding means to allow the pickup to engage the record, a pivotally mounted arm for the pickup, and a pivotal mounting for the carrier disposed in axial alignment with the pivoted mounting for the arm.

5. In combination, an arm, reproducing means connected to the arm for cooperation with a record, a carrier for said reproducing means arranged to hold said means out of cooperation with the record, and means for supporting said carrier so as to enable it to be swung independently of said arm about an axis common to both the arm and the carrier.

6. In combination, an arm, reproducing means connected to the arm for cooperation with a record, a carrier for said reproducing means arranged to hold said means out of cooperation with the record, and means for supporting said carrier so as to enable it to be swung about an axis common to both the arm and the carrier, said supporting means including a stop for limiting pivotal movement of said carrier.

7. In combination, an arm, reproducing means connected to the arm for cooperation with a record, a carrier for said reproducing means pivotally associated with said arm and arranged to hold said means out of cooperation with the record, and means for supporting said carrier so as to enable it to be swung about an axis common to both the arm and the carrier, said supporting means including a fixed tube upon which both the arm and carrier are pivotally mounted.

8. In combination, an arm, reproducing means connected to the arm for cooperation with a record, a carrier for said reproducing means arranged to hold said means out of cooperation with the record, and means for supporting said carrier so as to enable it to be swung about an axis common to both the arm and the carrier, said supporting means including a fixed tube having means for limiting the pivotal movement of both the arm and carrier.

9. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, and a mounting for said arm and carrier comprising a tube, said arm including an extension journaled inside of said

tube and said carrier including a mounting portion pivotally mounted on said tube.

10. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, a mounting for said arm and carrier comprising a tube, said arm including an extension journaled inside of said tube and said carrier including a mounting portion pivotally mounted on said tube; and stop means associated with said arm extension and said tube for limiting the movement of said arm about the axis of said tube.

11. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, a mounting for said arm and carrier comprising a tube, said arm including an extension journaled inside of said tube and said carrier including a mounting portion pivotally mounted on said tube, and stop means connected to said tube and associated with said mounting portion of said carrier for limiting the movement of said carrier about the axis of said tube.

12. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, a mounting for said arm and carrier comprising a tube, said arm including an extension journaled inside of said tube and said carrier including a mounting portion pivotally mounted on said tube, stop means associated with the arm extension and said tube for limiting the movement of said arm about the axis of said tube, and stop means connected to said tube and associated with said mounting portion of said carrier for limiting the movement of said carrier about the axis of said tube.

13. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, and a tubular insulation member connected to said supporting means arranged to have an electrical conductor for said carrier threaded therethrough, said tubular member being disposed eccentric with respect to said common axis.

14. In combination, an arm, reproducing means connected to the arm for cooperation with a record, a carrier for said reproducing means arranged to hold said means out of cooperation with the record, and means for supporting said carrier so as to enable it to be swung independently of said arm about an axis common to both the arm and the carrier, said carrier including adjustable means for enabling the carrier to support the reproducing means at various distances from the record.
15. In combination, an arm, reproducing means connected to the arm for cooperation with a record, a carrier for said reproducing means arranged to hold said means out of cooperation with the record, and means for supporting said carrier so as to enable it to be swung about an axis common to both the arm and the carrier, said carrier including adjustable means for enabling the carrier to support the reproducing means at various distances from the record, said reproducing means including an extension cooperable with said adjustable means and said adjustable means including a projection having on its top side a formed surface on which said extension is adapted to rest.
16. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, said supporting means including a fixed tube upon which both the arm and carrier are pivotally mounted, and a mounting for said fixed tube including stop means for limiting the pivotal movement of said carrier.
17. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, said supporting means including a fixed tube upon which both the arm and carrier are pivotally mounted, and a mounting for said fixed tube including stop means for limiting the pivotal movement of said carrier, said tube having its lower end provided with a slot arranged to cooperate with the arm and limiting the movement of the arm about the axis of said tube.
18. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, and a mounting for said arm and carrier comprising a tube, said arm including an extension journaled inside of said tube and said carrier including a mounting portion pivotally mounted on said tube, said extension comprising a tubular element connected to the arm at its axis and being arranged to have an electrical conductor threaded therethrough and into the arm.
19. In combination, an arm, reproducing means connected to the arm for cooperation with a record, a carrier for said reproducing means arranged to hold said means out of cooperation with the record, means for supporting said carrier so as to enable it to be swung about an axis common to both the arm and the carrier, a mounting for said arm and carrier comprising a tube, said arm including an extension journaled inside of said tube and said carrier including a mounting portion pivotally mounted on said tube, and a plurality of spaced anti-frictional elements in said tube between said extension and the internal surface of said tube.
20. In combination, an electrical pickup for reproducing the recorded waves on a given record, and a carrier associated with the pickup including means for holding the pickup out of cooperation with the record and electromagnetic means for releasing the holding means to allow the pickup to engage the record, said electromagnetic means including a reciprocable rod and an electromagnet for holding the rod in a given position when the electromagnet is energized, said holding means including a pivotally mounted element operable by said rod and arranged to hold said pickup out of cooperation with said record when said rod is in said given position.
21. In combination, an electrical pickup for reproducing the recorded waves on a given record, and a carrier associated with the pickup including means for holding the pickup out of cooperation with the record and means for releasing the holding means to allow the pickup to engage the record, said latter means including an electrically operable rod adapted to be held in a given position, said holding means including a pivotally mounted element having a cam portion engageable by said rod and said element being arranged to hold said pickup out of cooperation with said record when said rod is in said given position.
22. In combination, an electrical pickup for reproducing the recorded waves on a given record, and a carrier associated with the pickup including means for holding the pickup out of cooperation with the record and means for releasing the holding means to allow the pickup to engage the record, said latter means including an electrically operable rod adapted to be held in a given position, said holding means including a piv-

- totally mounted element having a cam portion engageable by said rod and said element being arranged to hold said pickup out of cooperation with said record when said rod is 5 in said given position, said rod including rollers for aiding in supporting said rod and for engaging said cam portion.
23. In combination an electrical pickup for reproducing the recorded waves on a 10 given record, means for engaging a portion of said pickup to hold it out of engagement with said record and electrically controlled cushioned means for gradually lowering said means to cause said pickup to engage the 15 record. 80
24. In combination an electrical pickup for reproducing the recorded waves on a given record, means for engaging a portion of said pickup to hold it out of engagement 20 with said record and electrically controlled cushioned means for gradually lowering said means to cause said pickup to engage the record including a pivoted arm having its free end engaging said portion of the pickup and 25 an element in cooperation with an intermediate portion of said arm to enable it to be gradually lowered. 85
25. In combination an electrical pickup for reproducing the recorded waves on a given 30 record, means for holding the pickup out of cooperation with the record and electromagnetic means for releasing the holding means to allow the pickup to engage the record, said electromagnetic means including a recipro- 35 cable element and an electromagnet for holding the element in a given position when the electromagnet is energized, said holding means including a pivotally mounted member operable by said element and arranged to 40 hold said pickup out of cooperation with said record when said element is in said given position. 90
26. In combination, an electrical pickup for reproducing the recorded waves on a 45 given record, means for holding the pickup out of cooperation with the record and means for releasing the holding means to allow the pickup to engage the record, said latter means including an electrically operable element 50 adapted to be held in a given position, said holding means including a pivotally mounted member having cam means engageable by said element and said member being arranged to hold said pickup out of cooperation with said 55 record when said element is in said given position. 100
27. In combination, an electrical pickup for reproducing the recorded waves on a given record, means for holding the pickup 60 out of cooperation with the record and means for releasing the holding means to allow the pickup to engage the record, said latter means including an electrically operable rod adapted to be held in a given position, said holding 65 means including a pivotally mounted 105
- member engageable by said rod and said member being arranged to hold said pickup out of cooperation with said record when said rod is in said given position, said rod including a roller for aiding and supporting said rod and for engaging said cam portion. 110
- In testimony whereof I have hereunto subscribed my name at Chicago, Cook County, Illinois.
